DESIGN FOR A TEXTILE FABRIC

George H. Perkins, Needham, Mass.

Application October 3, 1941, Serial No. 103,621

Term of patent 3½ years

To all whom it may concern:

Be it known that I, George H. Perkins, a citizen of the United States, residing at Needham, in the county of Norfolk, State of Massachusetts, have invented a certain new, original, and ornamental Design for Textile Fabrics, of which the following is a specification, reference being had therein to the accompanying drawing.

The drawing is a face view of a portion of the textile fabric showing my new design.

I claim:

The ornamental design for a textile fabric, substantially as shown.

GEORGE H. PERKINS.
